United States Patent Office.

GEORGE KAY AND JOSEPH KAY, OF ESOPUS, NEW YORK.

Letters Patent No. 60,905, dated January 1, 1867; antedated December 20, 1866.

IMPROVEMENT IN POCKET KNIVES.

The Schedule referred to in these Letters Patent and making part of the same.

TO ALL WHOM IT MAY CONCERN:

Be it known that we, GEORGE KAY and JOSEPH KAY, of Esopus, in the county of Ulster, and State of New York, have invented new and useful Improvements in Pocket Knives; and we do hereby declare that the following is a full, clear, and exact description thereof, which will enable others skilled in the art to make and use the same, reference being had to the accompanying drawings, forming a part of this specification.

The present invention consists in a novel manner of securing the spring or springs for holding the blades of a pocket knife in position, either open or closed, whereby the cost of manufacture is greatly decreased, and a much more efficient knife produced, as will be obvious from the following detail description thereof, reference being had to the accompanying plate of drawings, in which—

Figure 1 is a view of the inside of one of the side plates or pieces of the knife handle, showing the blade spring in connection therewith; and

Figure 2, a cross-section through the handle of the knife, taken in the direction of its length.

Similar letters of reference indicate like parts.

A A, in the drawings, represent the side plates or pieces of the knife handle, which are secured together at each end by means of rivets in the ordinary manner; in and between the rivet *a*, at the front end of the handle, and the raised lip or flange *b*, upon the back edge of one of the side plates A, one end of the bent spring B is firmly held, against the other and loose end, C, of which the knife blade acts as in ordinary pocket knives. The rivet *a*, when the handle is made of metal, may be cast or otherwise formed in connection with one side of the same, as well also as the raised flange or edge *b*, which is intended to be of sufficient depth to embrace the entire space or opening between the two side plates of the knife handle.

We claim as new, and desire to secure by Letters Patent—

The arrangement of the bent spring B between the rivet *a* and flange *b*, in combination with the side plates A A, constructed and operating in the manner and for the purpose herein specified.

GEORGE KAY,
JOSEPH KAY.
